(57) **CLAIM**

The ornamental design for a marker, as shown and described.

DESCRIPTION

FIG. 1 is a perspective view showing our new design for a marker;

FIG. 2 is a front view of the marker of FIG. 1;

FIG. 3 is a right side view of the marker of FIG. 1;

FIG. 4 is a rear view of the marker of FIG. 1;

FIG. 5 is a left side view of the marker of FIG. 1;

FIG. 6 is a top plan view of the marker of FIG. 1;

FIG. 7 is a bottom plan view of the marker of FIG. 1;

FIG. 8 is a perspective view of a second embodiment of the marker of FIG. 1;

FIG. 9 is a front view of the marker of FIG. 8;

FIG. 10 is a right side view of the marker of FIG. 8;

FIG. 11 is a rear view of the marker of FIG. 8;

FIG. 12 is a left side view of the marker of FIG. 8;

FIG. 13 is a top plan view of the marker of FIG. 8; and,

FIG. 14 is a bottom plan view of the marker of FIG. 8.

UNITED STATES PATENT AND TRADEMARK OFFICE
CERTIFICATE OF CORRECTION

PATENT NO. : Des. 584,771 S
APPLICATION NO. : 29/284151
DATED : January 13, 2009
INVENTOR(S) : Gerules et al.

Page 1 of 1

It is certified that error appears in the above-identified patent and that said Letters Patent is hereby corrected as shown below:

On the title page, in the Description delete lines 9-16, beginning with the description of Fig. 8-- Fig. 14.

In the drawings delete sheets 3 of 4 and 4 of 4, consisting of Figs. 8-14.

Signed and Sealed this

First Day of December, 2009

David J. Kappos
Director of the United States Patent and Trademark Office

UNITED STATES PATENT AND TRADEMARK OFFICE
CERTIFICATE OF CORRECTION

PATENT NO. : Des. 584,771 S
APPLICATION NO. : 29/284151
DATED : January 13, 2009
INVENTOR(S) : Gerules et al.

Page 1 of 4

It is certified that error appears in the above-identified patent and that said Letters Patent is hereby corrected as shown below:

Delete the title page and substitute therefore the attached title page showing the corrected number of Drawing Sheets.

On the title page, in the Description delete lines 9-16, beginning with the description of Fig. 8-Fig. 14.

Delete Drawing Sheets 1-4 and substitute therefore the attached Drawing Sheets 1 and 2 consisting of Figs. 1-7.

This certificate supersedes the Certificate of Correction issued December 1, 2009.

Signed and Sealed this
Twenty-second Day of December, 2009

David J. Kappos
Director of the United States Patent and Trademark Office
